UNITED STATES PATENT OFFICE

JOHN B. BROCHU AND MAX SHRIBMAN, OF SALEM, MASSACHUSETTS

TOP-SPINNING DEVICE

Application filed January 28, 1930. Serial No. 424,037.

Our invention relates to improvements in top spinning devices and has for its primary object to provide a novel and improved device of this character which will be very simple and inexpensive in construction, and highly efficient in practical use,—it being possible with the use of our device to keep a large number of tops spinning at the same time.

Another object of the invention is to provide a top spinning device which may be used with the ordinary top spinning cord and which obviates the necessity of applying the cord to substantially the entire conical portion of the top as is usually necessary,—thus making it possible to quickly arrange the cord to bring about the necessary co-relation between the cord and top to effect a spin of the latter.

The invention also resides in certain novel features of construction, combination and arrangement of the various parts and in modes of operation,—all of which will be readily apparent to those skilled in the art upon reference to the accompanying drawing in connection with the detailed description appearing hereinafter.

While the drawing illustrates the now preferred form of the invention,—yet it is to be understood that the same is capable of other mechanical expressions within the spirit and scope of the subject matter claimed herein-after.

In the drawings,

Figure 1 is a top plan view of a top spinning device incorporating our invention;

Figure 2 is a cross sectional view taken on the line 2—2 of Figure 1;

Figure 3 is a view similar to Figure 2 but showing the top in place and the cord applied ready for use;

Figure 4 is a bottom plan view showing the top in place;

Figure 5 is an end view; and

Figure 6 is a cross sectional view.

Referring specifically to the drawing,—wherein the same reference characters have been used to designate the same parts in all views,—numeral 2 designates a substantially rectangular block having a central conical recess 3^a adapted to receive a top 3 and commu-

nicating with a hole 4^a in the opposite surface of the block through which the stud portion 4 of the top projects when the body thereof is located in the recess 3^a.

As clearly shown in Figure 2 one edge of the block 2 is cut with two diagonal recesses 5 (or slots) which extend to a depth equal to thickness of the block, and communicate with top surface grooves 6 which are adapted to receive and guide the cord 7 located in the slots or recesses 5. The lower ends of the slots 5 are located upon opposite sides and adjacent the stud receiving hole 4^a while at the opposite surface of the block the ends of the slots 5 are adjacent the ends of the block.

The cord 7 is approximately thirty inches long and has a button or stop 8 at one end as shown.

In operation it will be evident that the intermediate portion of the cord is first twined around the stud 4 of the top as shown in Figure 3. The ends of the cord are then located in the slots 5 and the communicating top surface grooves 6 which serve to guide and locate the cord. The block will preferably be grasped in the right hand and the button 8 gripped with the other hand. A sharp pull on the cord 7 effects a spinning of the top,—it being evident that the length of cord between the stud 4 and button 8 will be substantially less than the length of cord on the opposite side of stud 4. The spinning of the top unseats same from the recess 3^a and it drops to the floor and spins as usual. The grooves 6 have their ends rounded adjacent slots 5 so as to reduce friction and obviate undue wear on the cord.

It will be apparent that the device can be made very cheaply and likewise that it will be practically indestructible.

Having thus described our invention what we claim as new and desire to secure by Letters Patent is:

1. A top spinning device comprising a block having a seating recess extending therethrough and forming a continuous aperture from the top to the bottom of the block, said block further having a plurality of diagonal slots extending therethrough from the top to the bottom and located on opposite sides

of the recess, said slots continued inwardly within the block from a side thereof so that the axial center of the recess and the inward terminals of the slots are in the same plane, and grooves formed in the top of the block communicating with the slots, the recess receiving the top and the slots and grooves a cord for actuating the top.

2. A top spinning device comprising a block having a conical recess forming an aperture from the top to the bottom of the block, and further having a plurality of diagonal slots also extending from the top to the bottom of the block and located on opposite sides of the recess, said slots continued inwardly within the block from a side thereof so that the axial center of the recess and the inward terminals of the slots are in the same plane, the slots being spaced closer to one another at the bottom than at the top of the block, grooves formed in the top of the block communicating with the slots, the recess adapted to receive the top and the slots and grooves a cord for actuating the top.

25 In testimony whereof we affix our signatures.

JOHN B. BROCHU.
MAX SHRIBMAN.
